(57) **CLAIM**

The ornamental design for camouflage tree bark relief hunting trousers, as shown and described.

DESCRIPTION

The present invention relates generally to camouflage hunting clothing, and more specifically, to camouflage hunting trousers having a relief pattern indicative of tree bark.

FIG. 1 is a front view of camouflage pine tree bark relief hunting trousers;

FIG. 2 is a rear view thereof;

FIG. 3 is a right side view thereof;

FIG. 4 is a left side view thereof;

FIG. 5 is a top view thereof; and,

FIG. 6 is a bottom view thereof.
